United States Patent Office

Des. 229,702
Patented Dec. 25, 1973

229,702

MINIATURE SHRINE OR THE LIKE

John T. Torlone, 37 Orchard St.,
Englewood, Ohio 45322

Continuation of design application Ser. No. 22,081, Mar.
27, 1971. This application June 1, 1971, Ser. No.
144,703

Term of patent 14 years

Int. Cl. D11—02
U.S. Cl. D29—23 A

Fig. 1

Fig. 2

Fig. 3

FIG. 1 is a front view of a miniature shrine or the like showing my new design;

FIG. 2 is a rear view of the shrine; and

FIG. 3 is a side view thereof.

This is a continuation of my copending application Ser. No. 22,081 now abandoned.

I claim:

The ornamental design for a miniature shrine or the like, substantially as shown and described.
